(57) **CLAIM**

The ornamental design for a guitar-shaped game controller body, as shown and described.

DESCRIPTION

FIG. 1 is a perspective view of a guitar-shaped game controller body showing our new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a bottom plan view thereof;

FIG. 7 is a top plan view thereof; and,

FIG. 8 is another perspective view thereof.

The broken lines indicate unclaimed portions and form no part of the claimed design.

1 Claim, 5 Drawing Sheets

FIG. 4

FIG. 5

FIG. 7

FIG. 6

FIG. 8
